PHONOGRAPH STOPPING MEANS

Lee B. Green, Lakewood, Ohio, assignor to The General Industries Company, Elyria, Ohio, a corporation of Ohio

Application July 16, 1940, Serial No. 345,742

3 Claims. (Cl. 200—153)

This invention relates to phonograph stopping means, and more particularly to an improved device for actuating an electric switch or other control member for automatically stopping the driving means of a phonograph or like machine after predetermined operation thereof such as when the stylus carried by the tone arm reaches the end of the sound track.

An object of my invention is to provide a stopping device, for a phonograph or like machine, which is designed for rapid and economical manufacture and which is sensitive and positive in operation and therefore well suited for actuation by a movable tone arm or like member.

Another object of my invention is to provide an improved stopping means for phonographs and the like in which a control-actuating member is biased toward the stopping position and is releasably held by a trip member mounted for rocking movement and adapted to be engaged by the tone arm.

A further object of my invention is to provide an improved phonograph stopping device having lever means adapted to be manually set and thereby biased to cause actuation of a control member and in which a sensitive trip member holds said lever in its set position but releases the lever when such trip member is engaged and shifted by the tone arm.

Still another object of my invention is to provide improved stopping means, of the character mentioned, in which the trip means for the control-actuating lever is arranged for transverse rocking movement and is biased by a transversely curved spring so as to form a releasable lock for the control-actuating lever.

My invention may be further briefly summarized as consisting in certain novel combinations and arrangements of parts hereinafter described and particularly set out in the appended claims.

In the accompanying sheet of drawings,

Fig. 1 is a partial plan view showing a phonograph having the stopping means of my invention applied thereto;

Fig. 2 is a plan view showing my improved automatic stopping device in detached relation and with the control-actuating lever in its set position;

Fig. 3 is a plan view thereof but showing the control-actuating lever in its released position;

Fig. 4 is a side elevation of the device;

Fig. 5 is an end view of the device with the control-actuating lever in its released or tripped position;

Fig. 6 is a transverse sectional view taken through the device as indicated by line 6—6 of Fig. 2;

Fig. 7 is a partial transverse sectional view taken on line 7—7 of Fig. 2; and

Fig. 8 is a perspective view showing a transversely curved spring embodied in the device.

As already indicated above, my improved stopping device is intended for use with a phonograph or like machine for automatically stopping the turntable after the desired period of rotation thereof such as when the stylus carried by the swinging tone arm approaches the end of the sound track. Fig. 1 of the drawing shows my improved stopping device 10 suitably mounted on the top or cover 11 of a phonograph having a rotatable turntable 12 and a swinging tone arm 13. The stopping device 10 may be located beneath the turntable 12, and as will be explained more fully hereinafter, has a projecting control-actuating lever 14 and a trip member 15 therefor provided with an arm portion 16 arranged to be engaged and moved by the tone arm 13 when the stylus 13a approaches the end of the sound track 12 of the record 12a lying on the turntable 12.

The embodiment of my stopping device shown in this instance is designed for use with an electrically driven phonograph and includes a control switch 18 by which the energizing circuit for the driving motor (not shown) can be closed to cause rotation of the turntable and can be opened to deenergize the motor and stop the turntable. The electric switch 18 may be of the snap action toggle type having a forked actuating member 19 projecting through an opening 20 of the switch casing. The switch also has terminal lugs 21 extending from the casing thereof and with which the conductors 22 of the motor circuit may be connected.

The stopping device 10 may be provided with a base plate or frame member 23 upon which the various parts of the device may be mounted and by which the device may be appropriately connected with the top 11 of the phonograph. The switch 18 may be located on the underside of the base plate 23 and may be connected with the base plate by means of ears or lugs 24 extending through appropriate openings or slots thereof. The base plate may have an opening 25 therethrough affording access to the forked toggle lever 19 from a point above the base plate.

The control-actuating lever 14 may be located above the base plate 23 and may be connected therewith by the pivot pin 26 upon which this lever can be swung. The lever includes an arm

27 which, at its inner or free end, has an angularly extending tongue or finger 28 deflected to extend downwardly through the opening 25 of the base plate and engaging between the arms or teeth of the forked toggle lever 18. A tension spring 29 having one end connected with the lever 14 and the other end anchored on the base plate 23 acts on the lever tending to swing the same on the pivot pin 26 in a clockwise direction from a set or running position, as shown in Figs. 1 and 2, to a released or stopped position as seen in Figs. 3 and 5. When the lever 14 is in its set position the contacts of the switch 18 are closed and the phonograph runs and when the lever is in its released position the contacts of the switch are open and the phonograph is stopped. The characteristics of the spring 29 are such that if the lever 14 is moved to its set position and thereafter released the spring will swing this lever clockwise and thereby actuate the forked toggle lever 18 to cause movement of the latter to the position corresponding with the open condition of the contacts on the switch 18.

For releasably holding or locking the controlling actuating lever 14 in the set or running position shown in Figs. 1 and 2, which corresponds with the closed condition of the contacts of the switch 18 and to which position the lever may be manually moved, I may provide the arm 27 of the lever with an elevated portion or strip 30 affording a shoulder 31 and may also provide the trip member 15 with a laterally offset latch portion or extension 33 which is engageable with such shoulder. The trip member 15 may be in the form of an elongated bar mounted on the upper side of the base plate 23 and arranged to have rocking movement relative to the latter and transversely of its own axis so that the latch portion 33 may be lifted to release or clear the shoulder 31 of the lever 14. For mounting the trip member on the base plate 23 with provision for such relative rocking movement, I may provide the latter with a pair of headed pins or rivets 34 projecting thereabove and extending through openings 35 of the trip member which are substantially larger in size than the cross-sectional dimension of the headed pins. The pins 34 extend above the base plate a distance which is somewhat greater than the thickness of the trip member so that the latter is capable of considerable movement toward and from the base plate as well as a rocking or tilting movement on the pins and transversely to its longitudinal axis.

To obtain efficient cooperation of the trip member 15 with the lever 14, I employ a spring 36 which acts on the trip member in a manner to cause positive engagement of the projection or latch portion 33 with the shoulder 31 whenever the lever 14 is swung to its set or running position as shown in Fig. 2. Very satisfactory results have been obtained by making the spring 36 in the form of a transversely deflected or curved plate spring, as shown in Fig. 8, and arranging the same between the trip member 15 and the base plate 23 so that the upstanding edge or portion 36a of the spring engages the trip member adjacent the outer edge thereof, that is to say along the edge thereof opposite that from which the latch portion 33 projects. By making the spring 36 of this form and arranging the same as just described and shown in Figs. 6 and 7, it will be seen that the spring seats against the face of the base plate 23 and the upstanding edge of the spring acts on the trip member 15 tending to rock the latter transversely on the pins 34 to

thereby swing or tilt the latch portion 33 downward toward the base plate so that it will drop into position behind the shoulder 31 as soon as the lever 14 is swung to the position shown in Fig. 2. The spring 36 may be retained between the base plate and the trip member 15 in various ways, but preferably is held in place by one pair of the ears or lugs 24 of the switch 18 and for this purpose I may provide the spring with holes 37 through which such ears or lugs extend.

As above mentioned, the trip member 15 may have an arm portion 16 for engagement with the tone arm 13 of the phonograph and although this arm portion may be integral with the trip member, I prefer to make it as a separate L-shaped part which may be connected with the trip member by means of the rivet 38. The connection formed by the rivet 38 may include a friction washer 39 and may be sufficiently tight that engagement of the arm 16 by the tone arm will cause rocking of the trip member 15 and yet not too tight to permit the arm 16 to be forcibly swung relative to the trip member for adjusting this arm to an angular position or setting for proper cooperation with the tone arm 13.

In the operation of the device above described, manual swinging of the lever 14 in a counter-clockwise direction on the pivot 26 to the position shown in Fig. 2 will actuate the switch 18 to close the contacts thereof and start the driving motor of the phonograph. Such movement of the lever 14 to this position also causes the spring 29 to be stressed and results in the latch portion 33 of the trip member 15 dropping into its locking position behind the shoulder 31 of the lever. The trip member now holds the lever 14 in its set position and the turntable 12 is rotated by its driving motor. Swinging of the tone arm 13 toward its dotted position shown in Fig. 1 causes it to engage the arm 16 of the trip member thereby rocking the trip member on the pins 34 and causing the latch portion 33 thereof to be lifted above the shoulder 31, as shown in Fig. 5, whereupon the spring 29 swings the lever 14 to its released position illustrated in Fig. 3 and thereby actuates the switch 18 to open the switch contacts and deenergize the driving motor.

From the foregoing description and the accompanying drawing, it will now be readily understood that I have provided an improved phonograph stopping device which is of very simple and economical construction but which is nevertheless capable of operating in a positive and satisfactory manner. By providing a relatively loose connection between the trip member and base plate and arranging the trip member for relative transverse rocking movement, it will be seen that the device will be very sensitive and very little force need be applied thereto by the tone arm to cause the desired automatic operation of the device. It will be seen furthermore that by the use of the transversely curved plate spring beneath the trip member the desired locking of the control-actuating lever will be automatically obtained by simply moving the lever to its set or running position and that the offset latch portion of the trip member will remain in locking engagement with the shoulder of the lever until the trip member has been rocked by the tone arm.

While I have illustrated and described my improved phonograph stopping device in a more or less detailed manner, it will be understood, of course, that I do not wish to be limited to the

particular details of construction and arrangements of parts herein disclosed, but regard my invention as including such changes and modifications as do not involve a departure from the spirit of the invention and the scope of the appended claims.

Having thus described my invention, I claim:

1. A control device of the character described, comprising a base plate having an opening therethrough, an electric switch beneath the plate, a switch actuating manually operated lever pivoted on said plate and having operative connection with the switch through said opening, a spring acting on said lever and urging the same toward one position of switch actuation, a trip member adapted to be engaged by said lever to prevent movement of the latter to said one position and being arranged for relative transverse rocking movement for releasing said lever, and a plate spring disposed beneath said trip member between said base plate and said trip member acting to rock the latter to a position to be engaged by said lever, said electric switch having lugs mounting the same on the base plate and serving also to connect said plate spring with the base plate.

2. A latch operated switch for phonographs of the type comprising a rotatable turntable, and having a tone arm associated therewith, said switch means mounted on a base plate located beneath said turntable, a lever pivoted on said plate and having operative connection with said switch, biasing means acting on said lever and adapted to swing the same in one direction to actuate the switch, a pair of spaced pins on said plate, an elongated trip member loosely mounted on said pins for rocking movement toward said plate to a position to be engaged by said lever for

holding the latter against movement by said biasing means and away from the plate to release said lever, and a plate spring between said base plate and trip member and tending to rock the latter toward the base plate, said trip member having an arm portion adapted to be engaged and shifted by the tone arm for causing rocking of the trip member away from the base plate.

3. A latch operating switch for phonographs of the type comprising a rotatable turntable and having a tone arm associated therewith, said switch means mounted on a base plate located beneath said turntable, said base plate carrying a switch actuating lever biased towards one position of switch actuation and a trip member rockingly mounted on the base plate and having transverse rocking movement with respect to the lever and to be lockingly engaged with said lever to prevent said lever from moving to said switch actuating position, said lever having a handle portion, which handle portion when manually moved in a counterclockwise direction causes the lever to actuate the switch and start the driving motor of the phonograph, such movement causing the trip member to move into locking engagement with said lever, said trip member maintained in such locked engagement with said lever during the record playing interval, an outwardly extending arm portion of said trip member adapted to be engaged by said tone arm at the conclusion of the playing interval whereby said trip member is rocked out of engagement with said lever and spring means associated with said lever to swing the lever to an inoperative position with respect to the switch means and stop the driving motor.
